William A. Darrah
Inventor.

UNITED STATES PATENT OFFICE

WILLIAM A. DARAH, OF CHICAGO, ILLINOIS

FUEL FIRED FURNACE

Application filed June 25, 1927. Serial No. 201,480.

This invention relates to equipment for heating materials by fuel and is particularly applicable to furnaces fired with gas, oil or powdered coal.

5 The object of this invention is to provide a simple, efficient, economical equipment for heating to high commercial temperatures with a minimum amount of oxidation of the material being heated. Another object of 10 this invention is to provide equipment which will transmit heat to the materials being heated in a relatively short time. Another object of this invention is to provide heating equipment such that the materials being heated will receive their heat mainly from 15 radiation and only in a small way from convection.

This equipment is particularly applicable to the melting of metals such as iron, alloys, 20 brass, aluminum, etc., but the principles disclosed herein may be applied to other operations, such as forging, heat treating, annealing, roasting, etc. It should be understood that this equipment is not limited to any 25 specific temperature or materials.

Referring to the drawing:

Fig. I shows a side elevation partly in section of one form of my device.

The section shown in Figure I is taken 30 along the line indicated in 1—1 in Figure II.

Fig. II shows a front elevation partly in section, the section shown is taken along section line 2—2 of Figure I;

Fig. III shows a plan view also partly in section; the section shown is taken along the line 3A—3A.

Fig. IV shows a section taken through the recuperator; the section shown is taken along line 4—4 of Figure I.

40 The form of my invention embodied on the drawing, comprises a furnace shell (1) equipped with a door (2) and mounted in a trunnion or bearing (3) in such a manner as to be able to oscillate either for discharging, charging or while heat is being applied.

A cylinder (4) which may be operated either by air, water or other convenient means serves to tilt the furnace in the desired manner. Air for combustion purposes is introduced in the furnace by pipe (5) and fuel

such as gas, oil or powdered material by pipe (6). Cylinder (4) is connected to a flange (7) at the rear portion of the furnace by a head (8) on the end of piston rod (9) which operates in cylinder (4).

Frame (1) is lined with refractory insulation as indicated on the sides of the furnace by (10), the bottom of the furnace by (11) and around the vertical shaft of the furnace by (12). Within the insulation is placed a refractory lining or support (13) and within the refractory lining or support is a special refractory material (14) which serves as a hearth or container for the materials being heated. An arch (15) is thrown over the hearth and insulated by heat resisting insulation (16) and low temperature insulation (17) in the manner shown. The top wall is formed with a series of projecting portions giving a serrated surface for purposes later to be described. One of these serrations is indicated by (18). A recuperator (19) formed of refractory material or heat resisting material is placed near the rear of the furnace, in the form shown on the drawing. The recuperator consists of a series of rectangular tubes as indicated by (20) although obviously any desired form or contour or arrangement may be substituted with similar results.

80 The air which enters the furnace by pipe (5) which is connected by a flexible tube or joint not shown passes around the recuperator through the space (21) between the recuperator tube (20) and the wall. The air travels downward in the direction shown by the solid arrows circling the tubes and leaves the lower portion of the recuperator by port (22) which directs it to the burner port (23). The fuel which for purposes of convenience 85 in this discussion will be assumed to be gas, enters through pipe (6) which may be attached to a flexible tube or hose or joint not shown. The gas travels through a refractory tube (24) placed within the air port (23) and so arranged that the gas leaves the end of the tube (24) and mixes with the heated air in combustion chamber (25).

90 The products of combustion travel longitudinally in combustion chamber (25) to

ward the front portion of the furnace and then travel upward at the end of combustion chamber (25). This path of travel is maintained by reason of a covering wall (26) which extends over the top of combustion chamber (25) at its rear portion, while an opening (27) is provided at the forward portion.

Combustion chamber (25) is formed between the outward wall of the furnace (28) and an inner combustion wall (29) which I prefer to make of a refractory material which is a good conductor of heat. Refractory wall (29) may to advantage be constructed from silicon carbide or other high conductive refractory material. I have found it convenient to build wall (29) from carborundum brick and to construct hearth (14) from carborundum cement. Obviously the entire stretch of lining formed by hearth (14) and wall (29) may be made of a refractory brick having the desirable heat conducting properties or both portions may be formed from a refractory cement.

When the gases leave combustion chamber (25) through opening (27) they travel in the direction shown by the arrows of Fig. I and IV backward under the arched roof of the furnace passing through series of flues (30, 31, 32, etc.) upward through the refractory recuperator tubes (20) leaving through opening (33) which serves as a vent or stack. The size of opening (33) is adjustable by means of a damper (24) which restricts the rate or flow of products of combustion from the furnace.

Arched roof (15) with projecting portions (18) becomes highly heated by the products of combustion as they leave the furnace, thus serving as a source of radiant heat which is, of course, radiated to material located in the hearth of the furnace. The side walls (29) also serve as a source of radiation, thus the back wall (35) which is heated by the products of combustion as they leave the furnace. At the same time, the hearth of the furnace serves as a source of conducted heat by reason of the fact that it is a good conductor in intimate contact with the combustion chamber. A spout or pouring lip (36) may be provided to direct the flow of melted material from the furnace in case the equipment is used as a melting device, also I wish it to be distinctly understood that the principles set forth in this specification may be applied to furnaces for a great variety of purposes and are not confined wholly to melting which, however, is one desirable application and has been chosen for purposes of description as a convenient means of illustrating this invention.

It will be noted that the furnace constructed in accordance with my invention provides means for consuming the fuel in combustion chambers in such a way that combustion does

not take place in contact with the material being heated. On the other hand, the material which it is desired to heat receives heat mainly by radiation as for example from the roof and sides of the furnace and also by conduction through the hearth of the furnace.

This construction permits a high efficiency in that combustion is complete in a properly designed combustion chamber and not retarded or influenced by the chilling effect of cool material such as the substance being heated. Products of combustion give up their heat to the surfaces of the furnace as for example the serrated roof thus causing this portion of the furnace to serve as a source of radiation. The serrations which are shown merely diagrammatically, as any desired contour or arrangement may be employed, serve to create eddies thus insuring intimate contact between the heated gases and the radiating surface. The serrations also serve to materially increase the radiating surface and the uniformity of the source of radiations. The serrations also serve in a measure as a heat storage, so that if the furnace is initially heated and a cold charge introduced, it is not always necessary to burn enough fuel during the heating of the cold charge as in many cases sufficient heat will be obtained from that stored in the furnace.

I also wish to point out that the arrangement by which the recuperator is constructed within the furnace permits the direct application of the heated air into the combustion chamber without involving the use of outside piping, fittings, valves, etc., which always serve as additional source from which heat may be lost or from which the air may leak. This construction also greatly simplifies the furnace.

In the case chosen for illustration I have shown a tilting furnace which is admirably suited for melting purposes. I have used such a furnace for melting glass, copper, iron, brass, aluminum and similar purposes.

It will be evident that by making simple constructions, the furnace may be used as a heating furnace as for example for forging, welding or similar operations.

One of the advantages of this furnace is the very material reduction in scaling or oxidation of the materials being heated. I have found that in the case of melting brass or heating steel a flame directed immediately on the substance being heated causes high losses due to oxidation or scaling. As a theory, which I believe to be correct, it would appear that the high losses which result in this case are due to the fact that certain portions of the surface of the materials being heated are raised to extremely high temperatures very rapidly, while an appreciable time is otherwise required for the heat to penetrate to the interior of the substance being heated.

Such an excessive heating of the surface naturally causes losses by scaling or oxidation.

On the other hand, in the furnace which I have invented, heat is radiated to the materials being melted and is radiated substantially uniformly and at controlled rates over substantially the entire exposed surface. Localized heating is, therefore, avoided and scaling, slagging, or oxidation is reduced.

10 As distinguished from this factor in my furnace, a stream of products of combustion gives intense local heating directly in its path and a much slower rate of heating at all points not directly in its path.

15 It will be apparent that many changes may be made in the structure shown and described without departing from the spirit of this invention and I do not wish to be confined to the exact arrangement disclosed herewith.

20 In referring to refractory materials I intend to designate such substances as fire brick, fire clay, sillimanite, silica, alumina oxide compounds, etc. In referring to heat conducting materials or materials of relatively 25 good heat conductivity, I intend to refer to such substances as silicon carbide, chrome oxide compositions, carbon and other dense homogeneous bodies, having a higher heat conductivity than ordinary fire clay.

30 Having now fully described my invention what I claim as new and wish to secure by Letters Patent in the United States is as follows:

35 1. A furnace comprising a housing, means for inclining said housing, a refractory hearth within said furnace, a combustion chamber adjacent said hearth, said combustion chamber having a heat conducting refractory wall adjacent said hearth, and a 40 roughened roof over said hearth, arranged to be heated by products of combustion from said combustion chamber.

45 2. A furnace consisting of a housing, a combustion chamber within said housing, a heating chamber within said housing, a heat conducting refractory wall separating said heating chamber and said combustion chamber, means for introducing fuel at one end of said combustion chamber, the products 50 of combustion passing through an opening formed near one end of said combustion chamber into said heating chamber and an exhaust port near the end of said heating chamber opposite said opening.

55 3. In a furnace a heating chamber arranged to be heated primarily by radiation, a combustion chamber separated from said heating chamber by highly heat conducting walls, a heat conducting hearth in said heating chamber, arranged to conduct heat from said combustion chamber to said heating chamber, a cover for a portion of the top of said combustion chamber and an outlet from said combustion chamber into said heating 60 chamber.

4. In a furnace a heating chamber, a hearth of heat conducting refractory material in said heating chamber, a combustion chamber adjacent said heating chamber and in contact with said hearth, said combustion chamber being located at one side of said heating chamber, and a cover over a portion of said combustion chamber, and an outlet being formed near the top portion of said combustion chamber communicating with the space above said hearth in said heating chamber.

5. A fuel fired furnace consisting of a refractory hearth, a heating chamber, a combustion chamber, said combustion chamber being arranged adjacent to and beside said heating chamber, a heat conducting refractory wall separating said combustion chamber from said heating chamber, a cover over a portion of the top of said combustion chamber, an outlet near the top of said combustion chamber communicating with the space above said hearth and within said heating chamber, and a container for enclosing said hearth and said combustion chamber.

6. In a furnace, a housing, a heating chamber within said housing, a combustion chamber adjacent and beside said heating chamber and within said housing, a refractory wall separating said heating chamber and said combustion chamber, means for introducing the fuel at one end of said combustion chamber, the products of combustion passing through an opening formed near one end of said combustion chamber into said heating chamber and an exhaust port near the end of said heating chamber opposite said opening.
